Application January 25, 1952, Serial No. 268,323

13 Claims. (Cl. 250—41.9)

(Granted under Title 35, U. S. Code (1952),
sec. 266)

1

The invention described herein may be manufactured and used by or for the Government of the United States for governmental purposes without the payment to me of any royalty thereon in accordance with the provisions of the act of March 3, 1883, as amended (45 Stat. 467; 35 U. S. C. 45).

The present invention relates to a mass spectrometer and more particularly to a mass spectrometer for the quantitative analysis of solids.

During the past 10 years the mass spectrometer has been applied with outstanding success to the rapid analysis of complex gas mixtures in research laboratories and in process control. As a result considerable interest has developed in its possible application to the analysis of solids, particularly metals. However, until now, none of the existing techniques has been found suitable for routine analytical work. The best available source of ions from solid materials is the vacuum spark, but the great variation in the intensity of the ion beam thus produced has restricted the spark source to methods employing photographic detection. The great variations in the intensity of the ion beam produced by the spark source have made it impossible to date to measure the quantity of one mass and then of another since there was no means for correlating the total number of ions present over the two periods of time. In the photographic methods, all of the masses to be measured are allowed to strike the photographic plate over the same period of time, each mass striking the plate at a different place because of separation in the magnetic field. Such methods are inherently limited in accuracy, convenience, speed, linearity of response, and range of concentrations that may be covered in one exposure. Moreover, the sensitivity of the photographic plate decreases for the heavier masses. These limitations have greatly restricted the use of mass spectrometers for the analysis of solids and have deterred the introduction of this technique into analytical laboratories.

An object of the present invention is to provide a mass spectrometer for the analysis of solids which automatically compensates for the variation in the intensity of the ion beam.

Another object of the invention is to provide fast and accurate means for the spectroscopic analysis of solids.

Another object of the invention is to provide a mass spectrometer for solids which can record directly on a graph.

In accordance with the present invention a con-

ventional mass spectrograph of the double-focusing type is modified in several respects. A monitoring collector is placed at the entrance to the magnetic analyzer and it provides a measure of the total ion current entering the analyzer. The magnetic analyzer has a single exit slit and ion collector, and the various masses to be measured are swept across this exit slit. The currents obtained from the two collectors are grounded through resistors and the voltages across these resistors are compared. An electrical rebalancing system responds to any changes in the relationship between these two voltages and records the ratios of the currents at the two collectors. Since any change in ion current due to fluctuations in the spark source will produce proportional changes in both currents, the ratio of the two currents will be relatively unaffected and the rebalancing system will not be energized.

Other uses and advantages of the invention will become apparent upon reference to the specifications and drawings.

Figure 1 is a side elevational view of the mass spectrometer.

Figure 2 is a top view of the machine taken along plane 2—2 of Figure 1.

Figure 3 is a view in perspective of the monitor collector.

Figure 4 is a top view of the monitor collector.

Figure 5 shows a diagrammatic cross section of the mass spectrometer and the machine's associated electrical apparatus.

Referring to Figures 1 and 2, 1 is the base of the machine. The two coils and magnetic poles that provide the magnetic field across the magnetic analyzer 5 are housed in the casings 2 and 3 and the base 1 and are energized by the variable source of current 10. The magnetic analyzer is supported between the casings 2 and 3 and therefore is subjected to the magnetic field set up between the two poles. The spark source is enclosed in the metal housing 4. This source is conventional and therefore is not shown in detail. The leads 6 and 7 carry the radio-frequency voltage needed to energize the spark source. The ions formed by the spark source are accelerated by the accelerating anode 8 which is located in the cylinder 9. The accelerating anode 8 (see Figure 5) is made up of two plates 11 and 12 which have slits 13 and 14 through which the ion beam 16 passes. The double plate is used so as to reduce the solid angle at which the beam emerges from the anode. The voltage for the accelerating anode is supplied between ground

and the lead 6 to the spark source. An electrostatic analyzer 15 which turns the beam through a 45-degree angle is located in the 45-degree elbow 17. The electrostatic analyzer is made up of two curved plates 18 and 19 which are supplied with a direct-current voltage over leads 21 and 22. The electrostatic analyzer directs the ion beam down the cylinder 26 and into the magnetic analyzer 5. Located at the entrance to the magnetic analyzer is the monitor collector 27 which is composed of plates 28, 29, and 31. A perspective view of these is shown in Figure 3. The top plate narrows the beam of ions that will enter the magnetic analyzer by having a slit 32 which is smaller than the cross-sectional area of the cylinder 26. The plate 29, which is located directly below plate 28, is a suppressor, the function of which is to reduce secondary emission from the collector plate 31. The voltage for the suppressor is supplied by the battery 30 through the lead 35. The slit in the suppressor is the same size as that in plate 28. The collector plate 31 is the last in the stack of three plates. The length of the slit 33 in this plate is shorter than those in plates 28 and 29 and therefore interrupts a part of the ion beam that passed through the slit 32. The purpose for this will be explained later. The relative sizes of the slits in plates 28 and 31 are shown by the top view of the monitor collector in Figure 4. The top plate is again 28. As can be seen, part of 31 extends into the opening under the slit 32. The location of the monitor collector 27 with regard to the rest of the machine is shown in Figure 2. The ion current collected on the plate 31 is supplied to an amplifier over lead 34.

A final ion collector 36, Figure 5, is located in the cylinder 37 just behind the plate 35, and the ion current collected there is fed to an amplifier over lead 38.

The entire path through which the ion beam travels must be evacuated and therefore the outlet 39 is provided for connection to vacuum pumps. Since it is desirable to be able to replace the rod that is to be ionized by the spark source without losing the vacuum in the entire machine, means are provided for sealing off the rest of the machine from the spark source area. A thumb screw 41 is connected to a slide valve 42 (Figure 5) which will cover the slit 23 when the thumb screw is turned. This seals off the spark area from the rest of the system. After the rod is replaced, this region can be evacuated through outlet 42. The thumb screw 43 controls the valve 44 in this outlet.

The operation of the mass spectrometer according to the present invention will be explained with reference to the diagrammatic cross section shown in Figure 5.

The material to be analyzed is formed into a rod 46 and ionized by a spark discharged between the rod, which forms one of the electrodes of the spark system, and the disk 47 which forms the other electrode. The radio-frequency oscillator 48 supplies the high voltage necessary for the creation of the spark discharge. The ions formed by the spark are accelerated through the slits 13 and 14. The accelerating potential is supplied between the anode plates 11 and 12 and the electrode 47 by the voltage supply 49. The stream of ions emerging from the slit 14 enters the electrostatic analyzer 15 and is deflected through a 45-degree angle by the electrostatic field established between the deflection plates 18 and 19.

The voltage for these plates is supplied by the voltage source 51. The electrostatic analyzer acts upon the ion beam in such a way that only ions lying within a definite predetermined energy range appear across the slit 32 in the plate 28. The ions with the lowest energy appear at the right side of the slit and those with the highest energy appear at the left side of the slit. The ions, after passing through the monitor collector, the operation of which will be explained later, enter the magnetic analyzer 5. The action of the magnetic field upon the ions is such that all ions of the same mass will appear at the same point along the diameter $d-d'$ of the magnetic analyzer. By correctly choosing the intensity of the magnetic field the ions of the desired mass will pass through the slit in plate 35 and be collected by the final ion collector 36. So much of the operation as has already been described is old and well known in the art and is common to most double-focusing mass spectrometers.

The present invention is concerned with the operation of the monitor collector and its related parts. As previously stated, the vacuum spark, although an excellent source of ions from solid materials, gives a widely fluctuating ion beam current, and mass spectrometers using such a source have not been considered practical. To make it practical to use the spark source with a mass spectrometer the present invention uses a monitor collector placed at the entrance to the magnetic analyzer. The monitor collector provides a method of measuring the ions of all masses that enter the analyzer. Referring now to Figures 3 and 4, the ion beam, after passing through the entrance slit 32, passes through the slit 33 in the plate 31. As previously stated, the entrance slit 32 determines the energy range of the ions that pass into the magnetic analyzer. This is controlled by the dimension "a" of the slit. On the other hand, the dimension "b" of the slit determines the magnitude of the ion current in that energy range that will pass into the magnetic analyzer. Since the "a" dimension of the slit 33 is at least as large as that of slit 32, while the "b" dimension is smaller, the plate 31 collects an ion current that has the same energy range as that passing into the magnetic analyzer. The portion of the ion current so collected contains ions of all the masses present and is directly proportional to the total ion current that passes through slit 33 and enters the magnetic analyzer. The current obtained from the monitor plate is amplified by the direct-current, phase-inverter amplifier 52 and then applied across the resistor 53, which is a part of a standard Brown recorder 56. The ions of the particular mass that is of interest at the moment are collected at the collector 36 and the resulting current is applied across the resistor 54.

As previously stated the amplifier 52 is a phase-inverted amplifier and as a result the voltage applied to the resistor 53 is negative with respect to ground. However, the voltage applied across resistor 54 for the output of the final collector 36 is positive and therefore the voltages across the resistors 53 and 54 are in opposition. If the voltage across 54 is equal to the voltage across the portion of 53 between the slider 62 and ground, the point 57 will be at ground potential and there will be no input to the amplifier 58. When the magnitude of the ion current collected at collector 36 changes, the voltage across the resistor 54 will change correspondingly. If an equal change in voltage has not taken place across that

portion of resistor 53 between slider 62 and ground, there is a signal input to the amplifier 58. This is fed to amplifier 59, where it is converted to alternating current, amplified, and fed to the motor 61. The motor drives the slider 62 until the voltages are again equal, at which time the slider again indicates the ratio between the two currents. At the same time the motor drives the slider it drives the pen of the recorder thereby producing a permanent record. As different magnetic fields are applied across the magnetic analyzer, this being accomplished by varying the source 10 shown in Figure 2, different masses will be directed to the collector 36. Since each mass will probably be present in different amounts the electrical system will be energized until the system is again rebalanced, at which time the slider will indicate the correct ratio. Since the monitoring collector receives an ion current composed of all masses, and the final collector receives the current corresponding to only one mass at a time, the two collectors receive currents that fluctuate in the same manner; that is, in the manner in which the source is fluctuating. The analysis is therefore comparatively free of errors due to fluctuation in the spark source. In other words, any changes due to fluctuations in the source will produce an equal change in voltages across the resistor 54 and across resistor 53 between the slider and ground. Consequently no signal will be introduced into the amplifier 58. As a result the motor 61 will not be energized, and the graph will not show any change. This system therefore minimizes errors that would result from the fluctuations of the source and makes it practical to use this type of source in a mass spectrometer.

The monitor collector that may be used is not restricted to the type shown and described. A grid placed across the entire opening of slit 31, or any other structure that collects a current that fluctuates in intensity in the same manner as the ion current in the magnetic analyzer, is suitable for this purpose. With any arrangement of this type the current collected by the monitor will be identical in every respect with that collected by collector 36 except that the monitor current will contain ions of all masses in the ion beam while the collector current will contain ions of only one mass.

The present invention is not restricted to use with a spark source. It may be used profitably with any source, since no source will be absolutely stable over long periods of time.

It will be apparent that the embodiments shown are only exemplary and that various modifications can be made in construction and arrangement within the scope of my invention as defined in the appended claims.

I claim:

1. A mass spectrometer which comprises a first means for producing ions of different masses from a substance, a second means for forming said ions into a beam, magnetic means for resolving the ion beam into beams of selected masses, a third means for producing a current that fluctuates in intensity in the same manner as the ion current in said magnetic means, a final collector, a fourth means including said magnetic means for directing one of said selected masses at a time to said final collector, and a fifth means for comparing the currents obtained from said third means and said final collector.

2. A mass spectrometer which comprises a first means for producing ions of different masses

from a substance, a second means for forming said ions into a beam, magnetic means for resolving the ion beam into beams of selected masses, a third means for producing a current that fluctuates in intensity in the same manner as the total ion current in said magnetic means, collector means for producing a current that fluctuates in the same manner as a beam of said selected masses, a fourth means including said magnetic means for directing one of said selected masses at a time to said fifth-named collector means and a fifth means for comparing the currents obtained from said third means with the current obtained from said collector means.

3. A mass spectrometer which comprises a first means for producing ions of different masses from a substance, a second means for forming said ions into an ion beam, magnetic means for resolving the ion beam into beams of selected masses, monitoring means comprising a collector which collects an ion current that includes all masses produced by said first means, a final collector, a third means including said magnetic means for directing one of said selected masses at a time to said final collector, and means for comparing the currents obtained from said monitoring means and said final collector.

4. A mass spectrometer which comprises means for producing ions of different masses from a substance, means for forming said ions into a beam, a magnetic analyzer for resolving the ion beam into beams of selected masses, a monitor collector comprising a collector which produces a current that fluctuates in the same manner as the total ion current entering said magnetic analyzer, a final collector, means including said magnetic analyzer for directing one of said selected masses at a time to said final collector, and rebalancing means for obtaining the ratio of the currents obtained from said monitor collector and said final collector.

5. A mass spectrometer which comprises means for producing ions of different masses from a substance, means for forming said ions into a beam, a magnetic analyzer for resolving the ion beam into beams of selected masses, a monitor collector comprising a collector which produces a current that fluctuates in the same manner as the ion current entering said magnetic analyzer, a final collector, means including said magnetic analyzer for directing one of said selected masses at a time to said final collector, resistor means for forming voltages from the ion currents collected at the monitor collector and the final collector, and means for comparing those voltages.

6. A mass spectrometer which comprises means for producing ions of different masses from a substance, means for forming said ions into a beam, a magnetic analyzer for resolving the ion beam into beams of selected masses, a monitor collector located between said second-named means and said magnetic analyzer, said monitor collector comprising a collector which produces a current that fluctuates in the same manner as the ion current entering said magnetic analyzer, a final collector, means including said magnetic analyzer for directing one of said selected masses at a time to said final collector, resistor means for forming voltages from the ion currents collected at the monitor collector and the final collector, and rebalancing means for comparing those voltages.

7. A mass spectrometer comprising means for producing ions of different masses from a sub-

stance, means for forming the ions into a beam, a magnetic analyzer for resolving the ions of each mass into separate ion beams, a monitor collector comprising a first and a second plate located between said second-named means and said magnetic analyzer, said first plate having a slit which allows a portion of said ion beam to pass through said first plate, said second plate having a slit which is smaller in one dimension than the slit in said first plate, said second plate therefore collecting a portion of the ions passing through said first slit, the portion collected being proportional to the total passing through said second slit, a final collector, means including said magnetic analyzer for directing the separate ion beams to the final collector at different times, resistor means for producing electric signals proportional to the ion currents collected at said second plate and said final collector, and rebalancing means for determining the ratio between said electric signals.

8. A mass spectrometer comprising means for producing ions of different masses from a substance, means for forming the ions into a beam with a continuous energy spectrum, a monitor collector comprising a first plate and a second plate, said first plate having a defining slit, one dimension of which determines the portion of the energy spectrum that will pass the first plate, the other dimension of which determines the ion current of the energy spectrum that will pass, said second plate having a defining slit which is smaller in the second-named dimension than said first slit, a magnetic analyzer which resolves the ion beam passing the slit in said second plate into beams of selected masses, a final collector, means including said magnetic analyzer for presenting the beams of selected masses at the final ion collector one at a time, resistor means for producing electric signals proportional to the ion currents collected on said second plate and said final collector and rebalancing means for determining the ratio between said electric signals.

9. The invention according to claim 8 in which the monitor collector has a third plate located between said first plate and said second plate, said third plate having a potential negative with respect to said second plate.

10. The invention according to claim 9 in which the means for producing the ions is a spark source.

11. A double-focusing mass spectrometer comprising a spark source for producing ions of dif-

ferent masses from a substance, an electrostatic analyzer for forming said ions into a beam with a continuous energy spectrum, a magnetic analyzer for resolving the ion beam entering said magnetic analyzer into beams of selected masses 5 a monitor collector located between said electrostatic and magnetic analyzers of said double-focusing mass spectrometer, said monitor collector comprising a collector that collects an ion current that is proportional to the ion current entering said magnetic analyzer, a final collector, means including said magnetic analyzer for presenting the beams of selected masses at the final ion collector one at a time, resistor means for producing electric signals proportional to the ion currents collected on said second plate and said final collector, and rebalancing means for determining the ratio between said electric signals.

12. A double-focusing mass spectrometer comprising means for producing ions of different masses from a substance, an electrostatic analyzer for forming said ions into a beam with a continuous energy spectrum, a magnetic analyzer for resolving the ion beam entering said magnetic analyzer into beams of selected masses a monitor collector located between said electrostatic and magnetic analyzers of said double-focusing mass spectrometer, said monitor collector comprising a first plate and a second plate, said first plate having a defining slit, one dimension of which determines the portion of the energy spectrum that will pass the first plate and the other dimension of which determines the magnitude of the ion current in the predetermined energy spectrum that will pass the first plate, said second plate having a defining slit which is smaller in the second-named dimension than said first slit, a final collector, means including said magnetic analyzer for presenting the beams of selected masses at the final ion collector one at a time, resistor means for producing electric signals proportional to the ion currents collected on said second plate and said final collector, and rebalancing means for determining the ratio between said electric signals.

13. The invention according to claim 12, in which the monitor collector has a third plate located between said first plate and said second plate, said third plate having a potential negative with respect to said second plate.
